UNITED STATES PATENT OFFICE.

JOHN HENRY ALLEN, OF NORTH YAKIMA, WASHINGTON.

ROTARY HARROW.

1,280,361.

Specification of Letters Patent.

Patented Oct. 1, 1918.

Application filed August 16, 1917. Serial No. 186,576.

To all whom it may concern:

Be it known that I, JOHN HENRY ALLEN, a citizen of the United States, residing at North Yakima, in the county of Yakima and State of Washington, have invented new and useful Improvements in Rotary Harrows, of which the following is a specification.

The present invention has reference generally to harrows and diggers and more particularly relates to a rotary harrow.

As the principal aim and object this invention contemplates the provision of a device of the above character the construction of which permits of the same being adjusted to assume a position for tilling the soil or to assume a position so as to be readily transported when desired without tilling or acting on the soil.

More particularly, this invention embraces the provision of a device of the above character wherein circular teeth carrying frames are employed and movably connected to the main supporting frame so as to be either swung into a horizontal operating or tilling position with respect to the main supporting frame or swung into a vertical position relative to the frame for facilitating the transportation of the frame.

As a further improvement this invention includes the provision of a rotary harrow wherein improved means are provided for removably fastening the axles longitudinally of the main frame or axle.

It is a more specific object of this invention to provide a device of the above character wherein the harrow frames are of novel construction to permit of the attaching of the soil treating teeth thereto in a convenient manner.

Among the other aims and objects of this invention may be recited the provision of a device of the above character with a view to compactness, and wherein the number of parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a con-

venient and satisfactory embodiment of the invention. It is to be noted in this connection that minor changes in the construction and arrangement of parts may be made without departing from the principle of operation of the various parts.

The invention is clearly illustrated in the accompanying drawings, in which:—

Figure 1 is a top plan view of the device in an operative or tilling position;

Fig. 2 is a front elevation thereof showing the device in a tilling position;

Fig. 3 is a front elevation of the same in a position ready to be transported;

Fig. 4 is an enlarged sectional detail taken on line 4—4 of Fig. 2; and

Fig. 5 is a horizontal section taken on line 5—5 of Fig. 4.

Similar characters of reference are employed in all of the above described views, to indicate corresponding parts.

Referring now, more particularly, to the accompanying drawings there is provided a main sectional frame indicated generally by the numeral 1 comprising a bar or timber 2 of a rectangular configuration in cross section and to the respective ends of which are connected channel sections 3, the latter being preferably straddled about and arranged in close relation with the under and side surfaces of the bar and rigidly secured in such position desirably through the instrumentality of transversely extending bolts 4 the projecting ends of which are engaged by nuts 5. The outer ends of the channel sections 3 are provided with inwardly extending recesses 6. Stub axles 7 are now employed being square in cross section and are each pivotally mounted at points midway their ends between the sides of the channel sections 3 adjacent the outer ends thereof by means of eye bolts 8 and are designed for vertical swinging movement so as to be removably arranged in the adjacent recesses 6 for a purpose that will presently appear. Filler blocks 8' are arranged about the bolts between the opposite sides of the axle and the side of the channel sections. The outer ends of the axles are reduced and journaled as at 9 forming shoulders 10 while harrow frames 11 are journaled on the reduced ends 9 of the axles and retained against accidental displacement by nuts 12.

In the present instance, each frame 11 is circular in form and constitutes a wheel consisting of a hub 13 journaled on the ad-

jacent reduced and rounded end 10 and provided with an annular groove 14 in its periphery. Arcuate channel sections 15 are now disposed in the grooves and accommodate radiating spokes 16 formed desirably of angle iron, the outer ends of which are cut away and bent to form flanges 17 while rims 18 are connected to the flanges at the outer ends of the spokes. A plurality of 10 teeth 19 are now employed and are connected at uniformly spaced intervals to the spokes 16 through the instrumentalities of U-bolts 20 and project at right angles from the outer side only of each spoke of the wheel as indicated. Subsequent to the arranging of the 15 harrow frames in position dust caps 21 are connected to the outer edges of the hubs. When the axles are arranged vertically of the main frame the teeth of the frames engage the ground for tilling purposes; however it is apparent that upon swinging of the axles to positions longitudinally of the main frame the harrow frames are positioned vertically of the main frame and act 20 as wheels for facilitating transportation. Bolts 22 are removably arranged transversely through the channel sections and the inner ends of the axles when the axles lie within these sections so as to be rigidly retained against accidental swinging. Filler 25 blocks 23 may be arranged about the bolts between the axle and the sides of the channel sections for preventing unnecessary movement while nuts 24 are employed for 30 engagement with the bolts.

Suitable means may be employed for moving the harrow, in the present instance a draft device being attached thereto which 35 consists of draw rods 25 the inner ends of 40 which are looped as at 26 and mounted in the eye bolts 8 while the outer portions are secured to the ends of a tongue support as at 27 preparatory to being rigidly connected upon opposite sides of a tongue 28 which 45 extends from the support 27.

The mode of operation of the present invention may be reviewed as follows:

Assuming that the parts have been assembled in the manner described and as indicated in the drawings, especially in Figs. 1 and 2, upon forward movement of the device the harrow teeth harrow or till the soil and if a rock is struck the entire harrow frame

11 will partially rotate on the corresponding 55 axle 9 until released. Inasmuch as the harrow frames are capable of being swung with respect to the main frame the harrow may be conveniently used, if desired, in the nature 60 of a pivoted sectional harrow, as is apparent. Upon the swinging of the axles into the adjacent sections 3 and the fastening of the 65 bolts 22 the harrow frames will be maintained in vertical positions with respect to the ground or at right angles to the main frame instead of parallel thereto, and since 70 these frames are circular and rotatably mounted they constitute wheels to facilitate the transportation of the device.

As many changes could be made in the 75 above construction and many apparently 80 widely different embodiments of this invention could be made without departing from the scope thereof, it is intended that all matter contained in the above description or 85 shown in the accompanying drawings shall 90 be interpreted as illustrative and not in a limited sense. It is also to be understood 95 that the language used in the following 100 claim is intended to cover all the generic and specific features of the invention herein described and all statements of the scope of the invention which, as a matter of language might be said to fall therebetween.

Having thus fully described this invention, what is claimed as new and desired to be secured by Letters Patent, is:—

A device of the character described including a sectional main frame composed of a bar and channel sections connected to the respective ends thereof and projecting therebeyond, axles pivotally mounted for vertical swinging movement at the outer ends of the channel sections, means for removably fastening the axles longitudinally of the channel sections, circular shaped harrow frames journaled on the axles and constituting wheels for facilitating the transportation of the device when the axles are positioned longitudinally, and teeth projecting at right angles from the outer sides 100 of the harrow frames for engagement with the ground when the axles are swung into a vertical position.

In testimony whereof I affix my signature.

JOHN HENRY ALLEN.

Copies of this patent may be obtained for five cents each, by addressing the "Commissioner of Patents, Washington, D. C."
